DOLLY FOR CANISTER TYPE CLEANERS

John L. Yonkers, Northbrook, Ill.

Application March 27, 1950, Serial No. 152,072

3 Claims. (Cl. 280—61)

1

This invention relates to a dolly for household appliances and particularly for canister type cleaners. Canister type cleaners generally have a cylindrical dirt receiving pail with a flexible hose leading from the side or top of the cleaner. Cleaners are usually dragged around by pulling on the hose. Because of the hose and the location of the electric motor and suction generating means, such devices are generally top-heavy and when moved may be tipped.

This invention provides a dolly which may be readily applied to or removed from a cleaner and which, when used, will permit the cleaner to be moved around readily with little effort while maintaining the cleaner in suitable position.

The dolly embodying the present invention is simple and inexpensive to tool for manufacturing the same in quantity. Furthermore, the dolly construction embodying this present invention is mechanically simple enough so that the average housewife may readily use it.

In order that the invention may be understood, reference will now be made to the drawings wherein Figure 1 shows a plan view of a dolly embodying the present invention supporting a canister type cleaner. Figure 2 is a perspective view of a dolly embodying the present invention. Figure 3 is a sectional detail upon line 3—3 of Figure 2. Figure 4 is a sectional detail upon line 4—4 of Figure 2.

Referring now to Figure 1, any type of canister cleaner, such as the one shown, may be used in connection with the dolly embodying the present invention. Thus the cleaner shown in Figure 1 comprises generally cylindrical dirt container pan having flexible hose 11 coupled by suitable means to the side of container 10. Means 12 may consist of a detachable coupling whereby the hose may be readily detached from or attached to the dirt containing pail. Resting upon top of pail 10 is assembly 15 consisting of an electric motor and suction generating means and suitable dust filtering means. This assembly may be retained on pail 10 by clamp 16. The cleaner is provided with handle 17 for handling or lifting.

For further details of a suction cleaner with which the dolly embodying the present invention may be used, reference may be made to Patent 2,198,568 of Yonkers.

In order to render the cleaner shown in Figure 1 readily movable and to provide a broader base upon which the cleaner may be supported, a dolly, generally indicated by numeral 20, may be provided. This dolly consists of a generally circular band of spring metal such as steel 21 having over-

lapping ends and riveted together at 22 and 23. As is evident in Figure 2, band 21 is formed generally cylindrical in shape about a vertical axis.

Disposed at spaced points, here shown as four, 5 are casters 25 to 28 inclusive. Each caster may be of conventional construction, consisting of roller 30 supported on pin 31 in yoke 32. Yoke 32 is carried by vertical pin 33. Each caster is supported in a fixture generally indicated by numeral 10 35. Each fixture 35 is preferably of sheet steel or the like and consists of vertical portions 36 and 37 joined by horizontal portions 38 and 39. Spaced upwardly from portion 39 is generally 15 U-shaped member 40 extending down between the bottom portions of 36 and 37. Portions 39 and 40 are apertured and support socket 41 vertically within which caster posts 33 may be disposed. In accordance with usual practice, socket 41 may have the usual means for locking caster 20 post 33 against falling out. Socket 41 has rubber washer 42 for spacing the socket head from portion 39.

Portions 39 and 37 of the fixture have extensions 43 and 44 going downwardly of the caster 25 as a whole and inwardly of metal band 21. These two supporting fingers are suitably apertured and have rubber pad 45 disposed therein in any suitable fashion. Thus pad 45 may have button shaped portion 46 adapted to be crowded into the apertures of the feet.

Portion 37 of the fixture is apertured at one or more places and provided with rubber buttons 50 and 51. The entire caster part is riveted to band 21 at 52.

Disposed over band 21 is molded rubber cover 55. This cover may be pulled over band 21 prior to riveting and provides a finished appearance.

As is evident from the drawings, a cleaner may be forced downwardly into the dolly and be frictionally engaged thereby to maintain the cleaner in position. By having four casters, stability of the cleaner is assured. In the event that it is desired to empty the cleaner of its dirt content, the entire cleaner may be readily removed from the dolly if desired, or the cleaner may be retained in the dolly indefinitely and otherwise handled in a normal manner. It is clear that the dolly may be safely used in a home without damage to furniture.

The generally circular band of spring steel is preferably distorted out of round somewhat, generally not enough to be readily recognizable by the eye. This makes it possible not only for a cleaner pan to be pushed down into position but 55 also allows for substantial manufacturing toler-

ances in the diameter of the pan. Any wear on rubber pads 50 and 51 will also be taken up. The fit of the band around a pan may be adjusted by distorting the shape of band 21.

What is claimed is:

1. A dolly for supporting a canister type cleaner or the like, said dolly comprising a generally circular band of flat spring metal, said band having its lateral dimension vertical in the normal use of the dolly, a plurality of fixtures carried by said band, each fixture having a flat strip of metal bent to provide two generally parallel vertical portions with at least one horizontal portion between said two vertical portions, means for rigidly securing one vertical portion on the circular band with the flat face of said one vertical portion being disposed against the flat face of the circular band at the region of attachment, said other vertical portion being inwardly spaced from the first vertical portion toward the center of said circular band, said fixture having a flat strip extending downwardly and inwardly from the bottom of one of said vertical portions and terminating in a supporting portion for the bottom of a canister, and means supported by the horizontal portion of said fixture for supporting said dolly on a floor, said last named means providing a small region of contact with the floor so that said dolly may be moved easily along a floor.

said fixtures being disposed at spaced intervals around said circular band, said other portion of each fixture being adapted to engage the outside of the canister.

5. The dolly according to claim 1, wherein the means for supporting the dolly comprises a caster.

10 3. The dolly according to claim 1, wherein the other vertical portion and the downwardly and inwardly extending portion contacting the canister sides and bottom are provided with rubber pads on the inside faces thereof where the canister is contacted.
